(57) **CLAIM**

The ornamental design for an automatic misting control system, as shown and described.

DESCRIPTION

FIG. 1 is a top, front and left side perspective view of an automatic misting control system, showing my new design; FIG. 2 is a bottom, rear and right side perspective view thereof;

FIG. 3 is another bottom, rear and right side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an explosive view thereof.

The broken lines show the features of the automatic misting control system that form no part of the claimed design.
